US0D1059703S

(12) **United States Design Patent** (10) **Patent No.:** **US D1,059,703 S**
Xu (45) **Date of Patent:** **** Jan. 28, 2025**

(54) **HIGH-PRESSURE CLEANER**

(71) Applicant: **NINGBO YINZHOU JIASHENG PUMP ELECTRIC MACHINERY FACTORY**, Ningbo (CN)

(72) Inventor: **Rongding Xu**, Ningbo (CN)

(73) Assignee: **NINGBO YINZHOU JIASHENG PUMP ELECTRIC MACHINERY FACTORY**, Ningbo (CN)

(**) Term: **15 Years**

(21) Appl. No.: **29/955,866**

(22) Filed: **Aug. 5, 2024**

(51) LOC (15) Cl. **15-05**

(52) U.S. Cl.

USPC **D32/15**

(57) **CLAIM**

The ornamental design for a high-pressure cleaner, as shown and described.

DESCRIPTION

FIG. 1 is a front, right and top perspective view of a high-pressure cleaner, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof; and,

FIG. 8 is an enlarged bottom plan view thereof.

The broken lines shown in the drawings illustrate portions of the high-pressure cleaner that form no part of the claimed design.

1 Claim, 8 Drawing Sheets
